United States Patent Office

Des. 221,617
Patented Aug. 31, 1971

221,617

SIGN HOLDER

Anthony N. D'Elia, 3555 Netherlands Ave., New York,
N.Y. 10471, and Edward M. Stolarz, R.F.D. 2, Horton
Drive, Yorktown Heights, N.Y. 10598

Filed Sept. 3, 1969, Ser. No. 18,980

Term of patent 14 years

Int. Cl. D8—03; D20—03
U.S. Cl. D8—243

FIG. 1

FIG. 2

FIG. 3

FIG. 4

FIG. 6

FIG. 5

FIG. 1 is a front elevational view of a sign holder embodying our new design;

FIG. 2 is a left side elevational view thereof;

FIG. 3 is a right side elevational view thereof;

FIG. 4 is a rear elevational view thereof;

FIG. 5 is a perspective view thereof; and,

FIG. 6 is a bottom plan view thereof.

The sign holder is shown broken away in part on the drawing to indicate indeterminate length.

We claim:

The ornamental design for a sign holder, as shown and described.
